US0D1039101S

(12) **United States Design Patent** (10) **Patent No.:** **US D1,039,101 S**
(45) **Date of Patent:** **** Aug. 13, 2024**

(54) **PROJECTILE LAUNCHER**

(71) Applicant: **Wrap Technologies, Inc.**, Tempe, AZ (US)

(72) Inventors: **Milan Cerovic**, Tempe, AZ (US);
David T. Richter, Tempe, AZ (US)

(73) Assignee: **Wrap Technologies, Inc.**, Tempe, AZ (US)

(**) Term: **15 Years**

(21) Appl. No.: **29/802,117**

(22) Filed: **Aug. 3, 2021**

(51) LOC (14) Cl. **22-01**

(52) U.S. Cl.

USPC **D22/100**

(58) **Field of Classification Search**

USPC D21/567, 570; D22/100, 117, 199

CPC F42B 12/66; F41B 15/04; F41H 13/0012

See application file for complete search history.

(57) **CLAIM**

The ornamental design for a projectile launcher, as shown and described.

DESCRIPTION

FIG. 1 is a perspective view of a projectile launcher in accordance with our invention;

FIG. 2 is a rear view thereof;

FIG. 3 is a front view thereof;

FIG. 4 is a top view thereof;

FIG. 5 is a bottom view thereof, and,

FIG. 6 is a side view thereof, an opposing side view being

a mirror image thereof.

The dashed lines and the unshaded areas adjacent to them in the drawings show environmental structure that forms no part of the claimed design.

1 Claim, 4 Drawing Sheets
